ATTORNEY

UNITED STATES PATENT OFFICE.

LOUIS RENARI, OF SANTA ROSA, CALIFORNIA.

WIRE STRETCHER.

Application filed July 1, 1924. Serial No. 723,492.

To all whom it may concern:

Be it known that I, LOUIS RENARI, a citizen of the United States, residing at Santa Rosa, county of Sonoma, State of California, have invented certain new and useful Improvements in Wire Stretchers; and I do declare the following to be a full, clear, and exact description of the same, reference being had to the accompanying drawings, 10 and to the characters of reference marked thereon, which form a part of this application.

This invention relates to improvements in devices for stringing and stretching wires 15 along fences, my principal object being to provide a wheel-supported device for the purpose arranged to carry a turnable reel of wire to be strung, so that by moving the device along the ground, the reel will rotate and the wire will be unwound therefrom. The device also carries permanently mounted means for engaging the wire after it has been strung for a suitable length, and enabling the wire to be drawn as taut as 25 may be desired.

By means of this device therefore, a reel of wire may be mounted on the same when leaving headquarters of the supply house, taken out to the scene of operations, and the 30 wire strung along the fence, without any physical effort on the part of the operators being necessary in so doing, since the device is adapted to be drawn by draft animals or other suitable means.

The wire tightening means on the device is 35 hand actuated, but is so arranged that great pulling pressure may be exerted on the wire without any great physical effort being necessary.

I have particularly in mind to apply my 40 wire stretching elements in connection with the post puller, as shown in my pending application on the same, filed May 21st, 1924, Serial No. 714,804, without interfering in any way with post pulling operations.

It will be evident, however, after a perusal of the following description, that the wire stretching device may be built as a 45 separate structure from the post puller. The assembling of the two features in one machine however saving the users the additional cost entailed by purchasing two machines, parts of which are or can be duplicated.

A further object of the invention is to 50 produce a simple and inexpensive device

and yet one which will be exceedingly effective for the purpose for which it is designed.

These objects I accomplish by means of 60 such structure and relative arrangement of parts as will fully appear by a perusal of the following specification and claims.

In the drawings similar characters of reference indicate corresponding parts in 65 the several views:

Fig. 1 is a side view of the wire stretching device as mounted in connection with a post puller.

Fig. 2 is a cross section of the same.

Fig. 3 is a detached top plan view of reel-supporting brackets, showing a means for 70 braking the rotative action of the reel.

Fig. 4 is a side elevation of the machine, 75 in operation.

Fig. 5 is a fragmentary top plan view of the frame of the structure, showing the independent wire clamping elements thereon.

Referring now more particularly to the characters of reference on the drawings, the 80 numeral 1 denotes a horizontal frame member, forked at its rear end in a horizontal plane to support post-pulling wedge-blocks 2, as featured in the above identified pending application.

The frame is supported intermediate its 85 ends on oppositely disposed wheels 3.

Depending from the frame and mounted thereon for lateral swivel movement are 90 transversely spaced brackets 4 arranged at their lower ends to removably seat a shaft or spindle 5 for a wire reel 6 of standard form.

The brackets are caused to be drawn together at their lower ends, so as to bear 95 against the opposite ends of the reel and exert a braking action thereon, by means of a horizontal hand-controlled lever 7 pivoted under the frame 1 ahead of the reel, and connected to the brackets by suitable link 100 means 8, which are connected to said lever equal distances on both sides of the pivot thereof. The brackets are positioned so that the reel therein will not interfere with post pulling operations, though the reel is of 105 course easily removed from the brackets at any time by withdrawing the spindle 5.

A horizontal rack 9 is slidably mounted 110 on the frame for longitudinal movement between guides 10, movement being imparted to the rack by a pinion 11 mounted on the frame 1 and connected to a turning handle

12. A pawl and ratchet mechanism 13 is mounted in connection with the pinion to normally prevent rotation thereof in other than that direction which will advance the 5 rack toward the forward end of the frame.

Mounted on the rack at the rear end thereof is a wire clamping means of any suitable character, such as for instance an eccentrically mounted disc or cam 14 having 10 a handle 15 whereby it may be turned to clamp the wire 16 of the reel between said cam and a fixed plate or block 17. Any other desired type of wire clamp may however be employed.

15. Another similar wire clamping means 18 is mounted on the frame 1 to the rear of the rearward limit of movement of the rack.

In operation the machine, with the wire reel mounted thereon, is wheeled to position 20 adjacent the first post 19 of the fence to be strung, with the rear end of the machine facing the post. The end of the wire on the reel is then attached to the post at the desired level, and the machine is then drawn 25 away from said post parallel to and adjacent the fence. With this movement of the machine, the reel of course rotates to allow the wire to unwind therefrom, the lever 7 being manipulated by the operator if necessary to prevent a freedom of rotation of the reel such as would cause the wire to be payed out too fast as to become tangled.

When the desired length of wire has been payed out, the machine is halted, and secured 30 against backward movement by any suitable means, such as by hitching the forward end of the frame to a dead man post 20, as shown in Fig. 4.

The end of the strung wire, which is 40 slack, is then caught up, and clamped between the clamping means on the rack, the latter being at its rearmost limits of travel.

The handle 12 is then turned so as to cause the rack to be advanced, and the 45 frame on which the rack is mounted being not stationary, the wire is of course tightened up. If the wire, upon the arrival of the rack at its forward limit of movement, is not under sufficient tension, said wire is placed and clamped between the fixed 50 clamping means 18 on the frame while the rack-clamp is loosened, the rack retracted, and the clamp thereon again tightened 55 against the wire. The clamp 18 is then loosened, and the rack again advanced. This operation may of course be repeated as

many times as may be necessary, without the machine as a whole being moved while so doing.

Although this device is shown and described for use in connection with barbed wire, the stretching structure may be employed to stretch wire field-fencing of various kinds.

From the foregoing description it will be 65 readily seen that I have produced such a device as substantially fulfills the objects of the invention as set forth herein.

While this specification sets forth in detail the present and preferred construction 70 of the device, still in practice such deviations from such detail may be resorted to as do not form a departure from the spirit of the invention, as defined by the appended 75 claims.

Having thus described my invention what I claim as new and useful and desire to secure by Letters Patent is:

1. In a wire stretching device having a frame supported from the ground and on which the stretching means is mounted, opposed brackets depending from the frame, and pivotally mounted therein for transverse movement, said brackets being arranged to support a wire-reel therebetween, 80 and means for moving the brackets laterally toward the reel at will, such means comprising a lever pivoted intermediate its ends on the frame, and connections between said lever on both sides of the pivot thereof and 85 the brackets.

2. In a wire stretching device having a frame supported from the ground and on which the stretching means is mounted, opposed brackets mounted on and depending from the frame and arranged to support a wire reel therebetween, and means for moving 95 said brackets laterally toward the reel at will to frictionally engage the same and impart a braking action thereto.

3. In a wire stretching device having a frame supported from the ground and on which the stretching means is mounted, opposed brackets depending from the frame, said brackets being substantially V shaped 105 and being formed at their lower ends with substantially U shaped bearing sockets, whereby to turnably and removably receive the shaft of a wire-reel.

In testimony whereof I affix my signature.

LOUIS RENARI.
